UNITED STATES PATENT OFFICE.

NORA LEAH KENNER, OF CORDELL, OKLAHOMA.

DISHWASHER.

Application filed March 29, 1922. Serial No. 547,693.

To all whom it may concern:

Be it known that NORA LEAH KENNER, a citizen of the United States of America, residing at Cordell, in the county of Washita 5 and State of Oklahoma, has invented new and useful Improvements in Dishwashers, of which the following is a specification.

The object of the invention is to provide a simple and efficient means whereby dishes 10 and like breakable articles may be cleansed mechanically or without manual contact or manipulation under conditions resulting in thorough sterilization without the risk of fracture, and may then be withdrawn from 15 the washing or rinsing water and drained and dried without handling; and with this object in view the invention consists in a construction and combination of parts of which a preferred embodiment is shown in 20 the accompanying drawings, wherein:—

Figure 1 is a side view partly in section of an apparatus embodying the invention.

Figure 2 is an end view.

Figure 3 is a detail sectional view of the 25 operating mechanism.

Figure 4 is a detail plan view of the carrier.

The apparatus consists essentially of a stationary receptacle or vessel 10 which as 30 illustrated may be supported upon a suitable framework consisting of the legs 11 and braces 12 in which is mounted a rotary carrier or cage 13 designed to receive the dishes or articles to be cleansed and provided 35 with suitable racks or bars 14 for facilitating the stacking and holding of the articles in proper positions to afford access of the water or cleansing liquid to the surfaces thereof, said carrier or cage being provided with a 40 tubular shaft 15 mounted for sliding movement upon a spindle 16 disposed axially in the receptacle or vessel 10, in connection with operating means 17 for communicating rotary motion to the carrier and lifting means 45 18 for removing the carrier or cage from the receptacle or vessel to permit of the draining and drying of the contents thereof.

In the illustrated embodiment of the invention the tubular shaft 15 of the carrier or cage (adapted to be covered when positioned in the vessel or receptacle 10 by means of a cover 19 fitted on the latter and having an inverted conical upper surface to afford drainage toward the central opening 20 55 through which the said shaft extends), is provided with a bevel pinion 21 with which

meshes a bevel gear 22 having a shaft 23, which is mounted in a bearing in a sleeve 24 which receives the upper end of the tubular shaft 15, and which extends into a slot 25 formed in a standard 26 which rises at one side of the receptacle or vessel with a bearing 27 at the lower end thereof to support the shaft when in operative position or when the shaft is being turned to impart rotary motion 60 to the carrier. An operating crank arm 28 is provided with a sleeve 29 fitted on the gear wheel-spindle 23 and having a clutch connection with the shaft by means of notches 30 therein arranged for engagement with 70 radial pins 31 on the shaft. By means of the sleeve it is obvious that the crank may be moved out of operative connection with the shaft by disengaging the members of the clutch to permit of independent rotation of 75 the carrier.

When the parts are in the washing position indicated in Figure 1 in full lines with the shaft of the driving gear 22 in the bearing at the lower end of the slot in the standard 26 it may be locked in place by means of a latch 32, so that vibration of the shaft incidental to the rotary motion thereof may be prevented. When it is desired to raise the carrier with its contents out of the 80 liquid contents of the receptacle or vessel 10 the latch may be disengaged from said drive shaft, and thereupon a lever 33 forming a part of the lifting mechanism and which is pivoted as at 34 upon the upper end of the 85 standard 26 may be moved from the full line position indicated in Figure 1 to the dotted line position therein, said lever being connected by a suitable link 35 with the sleeve 24. The elevation of the sleeve carries with it the tubular shaft which supports the carrier, and also carries with it the drive shaft to occupy the elevated position indicated in dotted lines in Figure 1. The lid or cover 19 of the receptacle or vessel 10 in 90 addition to having the central opening 20 for the tubular shaft of the carrier is radially slotted as indicated at 20^a to permit of application and removal thereof, and obviously when it is desired to raise the carrier for the purpose of draining the contents thereof the cover should first be removed, and after the lifting lever has been actuated as herein-above indicated the cover may be 95 replaced to serve as a support for the carrier, and as said cover is inclined toward its center to form a drainage surface and the 100 105 110

walls and bottom of the carrier are perforated to permit of the circulation of water or cleansing liquid in the vessel, the moisture will readily drain from the contents of the carrier when thus supported in an elevated position and will pass back into the vessel and leave the dishes in a dry condition provided of course the water from which they have been withdrawn is of a sufficiently high 10 temperature. Or after the carrier has been raised to the draining position subsequent to the washing operation which is conducted by a more or less rapid rotation of the carrier in the liquid contents of the receptacle, boiling or other hot rinsing water may be poured over the dishes in the carrier and permitted to drain back into the vessel or receptacle.

Having described the invention, what is claimed as new and useful is:—

- 20 1. A dish washing apparatus having a vessel or receptacle for cleansing liquid, a rotary carrier or cage mounted in the vessel or receptacle for axial movement to a position above the liquid contents thereof, operating mechanism for imparting rotary motion to the carrier or cage, and lifting mechanism for raising the carrier or cage to its elevated position, the carrier or cage
- 25

having an axial shaft and means for supporting the same for axial movement, and a sleeve embracing the upper end of said shaft, and said operating mechanism having a drive shaft geared to the carrier shaft and mounted at its inner end in a bearing in said sleeve, the said drive shaft being mounted at its outer end in a slotted standard, and means being provided for holding said shaft against displacement when the carrier is in its operative position.

2. A dish washing apparatus having a 40 vessel or receptacle for cleansing liquid, a rotary carrier or cage mounted in the vessel or reception for axial movement to a position above the liquid contents thereof, operating mechanism for imparting rotary motion to the carrier or cage, and lifting mechanism for raising the carrier or cage to its elevated position, the carrier having a shaft, and a sleeve having a swivel connection with the shaft, and the lifting mechanism having 45 a lever operatively connected with said sleeve.

In testimony whereof she affixes her signature.

NORA LEAH KENNER.
